UNITED STATES PATENT OFFICE.

PAUL M. BEARD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR END CONSTRUCTION.

1,208,899.

Specification of Letters Patent. Patented Dec. 19, 1916.

Application filed May 28, 1915. Serial No. 30,95..

To all whom it may concern:

Be it known that I, PAUL M. BEARD, a citizen of the United States, residing at the city of St. Louis, State of Missouri, have 5 invented a certain new and useful Improvement in Car End Construction, of which the following is a full, clear, and exact description, such as will enable others skilled in the art to which it appertains to make and 10 use the same, reference being had to the accompanying drawings, forming part of this specification.

My invention relates to railway car construction, and pertains particularly to the 15 construction of sheet metal ends for box cars.

The principal object of my present invention is to provide a construction wherein the end is made up of corrugated or ribbed sections of sheet metal which are secured together in such fashion as to form a beam whose members are formed by portions of the sheet metal, and which are so constructed as to insure them against failure under 20 service conditions.

Another object of my invention is to provide an improved means for securing ends to cars, the object of which is to facilitate attachment and detachment in construction and repair.

A further object of my invention is to provide an end constructed in such fashion as to reinforce the framing members to which it may be attached in the car superstructure.

Other objects of my invention will be obvious or pointed out hereinafter.

Two forms of my invention are illustrated in the accompanying drawings wherein—

Figure 1 is a front elevation of a car end embodying my invention; Fig. 2 is an elevational section thereof taken approximately on line 2—2 of Fig. 1; Fig. 3 is a detail showing a cross section at the corner of a car substantially on line 3—3 of Fig. 1, and including a portion of the girth strip in section at a side or transom post. Fig. 4 is a detail illustrating a modification; Fig. 5 is a detail illustrating a feature of the attaching means.

In the car end illustrated in the drawings, 50 1 represents an upper section and 2 represents a lower section, both of sheet metal, which have their adjacent edges flanged outwardly and in L-form, as illustrated in Fig. 2, as departing portions 4 and joining portions 5. The joining portions 5 are over-

lapped and secured together, and form a tension member disposed in a plane removed from the major plane of the sections. Disposed transversely of the beam are corrugations 6 which may be faded or merged into the departing portions 4, or may terminate adjacent thereto. These corrugations 6 operate to stiffen the sections 1 and 2 transversely, and to transmit the stiffening influence of the beam across them. A connecting strip 7 is disposed against the inner faces of the sections and connected thereto at the inward sides of the departing portions 4, thereby tying the sections together approximately in their major plane across the outwardly pressed marginal portions. This connecting strip extends the entire length of the end wall, and preferably is attached to the corner posts, together with the side flanges 8 of the sections. This connecting strip forms a compression member which cooperates with the tension member formed by the overlapped and connected portions 5 to provide a beam extending longitudinally of the sections across the car end at the junction of the sections, and operating to greatly strengthen and stiffen the end against various service shocks.

I refer to the tie strip 7 as the compression member, and the member formed by the portions 5 as the tension member of the beam, for the reason that the strip 7 is normally put under some slight compression when the end is affixed to the car, and the major service shocks, which are the stresses imparted to the end by shifting of the cargo thereagainst, also place the connecting strip 7 under compression and the member formed by the portions 5 under tension. Due to the fact that the member 7 is frequently, if not normally, under appreciable compression, which would render it liable to failure if started by a local strain, I provide means for stiffening and reinforcing said connecting strip against such failure. To this effect I provide the strip 7 with transverse corrugations 9 pressed outwardly and of such length as to be accommodated between the departing portions 4. The disposal of these corrugations 9 may be as desired, either intermediate or aligned with the transverse corrugations 6. These corrugations 9 so stiffen the connecting strip 7 as to prevent failure of the beam from a local strain therein. Said corrugations 9 also provide

additional strengthening members disposed approximately in the major plane of the sections, thereby giving the structure as a whole additional strength in lines transversely of 5 the sections.

As illustrated in Fig. 2, the lower margin of section 2 is normally riveted to the upper portion of the car end sill 10. In service it frequently occurs that violent thrusts against 10 the end will bend the web of the end sill, throwing the upper portion of the sill outwardly. As a means for further resisting such thrusts and taking a portion thereof from the end sill, I provide the corrugations 15 11 pressed inwardly at the corner where the margin of the section is flanged rearwardly to provide the bottom flange 12. These corrugations form connecting gussets between the vertical wall of the section and the 20 flange, stiffening the metal across the corner so as to prevent its bending on the corner and on the line of the fastenings which connect it to the end sill. The flange 12 being secured in position to the floor framing 25 members illustrated in dotted lines in Fig. 2, the construction will operate to relieve the end sill of an appreciable amount of bending stress imparted by load thrusts.

My improved arrangement for connecting 30 the sections to the car superstructure at the ends of the beam member, is illustrated in Figs. 3 and 5. The corner posts 14 and side posts 15 are slotted for the passage of a metal girth strip 16 which is seated therein, 35 extending back from the end as far as desired. This girth strip is bolted to the posts and has bolted to it at either side furring strips 17. These strips provide material to which the lining 18 and sheathing 19 may 40 be nailed. The ends of these girth strips project beyond the corner posts and are turned over as is illustrated at 20 in Fig. 3. At suitable points to receive these projecting 45 ends, the members 5 of the sections are provided with apertures 21 adapted to permit the passage therethrough of the turned-over portions. When the end is applied to the car, the side flanges 8 are bolted to the corner posts, the ends of the strips 16 projecting 50 through the apertures 21. A keeper 22 having a pocket for the reception of the bent-over end 20 is then placed in engagement with said bent-over end and is riveted or bolted to the members 5. This construction 55 forms a very secure attachment of the sections to the car superstructure immediately at the ends of the beam member. At such times as it becomes necessary to remove the end for repairs, the sections are readily freed 60 from this attachment by simply detaching the keeper 22, which will permit the withdrawal of the sections from the projecting ends of the girth strips.

In the modification illustrated in Fig. 4, 65 the tension member is formed entirely by the

lower portion of the section 1', and the compression member 7' is formed by a continuation of the section 2' which bridges the space between the departing portions 4' and is secured to section 1' at opposite sides of said portions 4'. The corrugations 9 are pressed in this extension 7' so as to lie between portions 4'. 70

I am aware that the device is capable of various modifications and changes not herein specifically illustrated and described, without departing from the spirit and scope of the invention. 75

What I claim is:

1. In a car end, a pair of sheet metal sections having portions adjacent their meeting edges displaced from the major plane of the sections, and their meeting edges secured together, a tie strip spanning said displaced portions and secured to the respective sections, said tie strip being provided with stiffening corrugations. 80 85

2. In a car end, a pair of sheet metal sections having portions adjacent their meeting edges displaced from the major plane of the sections, and said meeting edges secured together to form a tension member, a tie strip disposed substantially in the major plane of the sections and connected to the sections to form a compression member, said tie strip being provided with stiffening corrugations. 90 95

3. In a car end, a pair of sheet metal sections having their meeting edges secured together in a plane apart from the major plane of the sections to form a tension member, a tie strip connecting said sections substantially in their major plane to form a compression member, said tie strip being provided with stiffening corrugations. 100

4. In a car end, a pair of sheet metal sections having their meeting edges secured together in a plane apart from the major plane of the sections to form a beam member, a tie strip connecting said sections substantially in their major plane to form a coöperating beam member, said tie strip being provided with stiffening corrugations, and means for securing said beam members at their extremities. 105 110

5. In a car body, in combination with vertical frame members, a girth strip passing through and secured to said vertical frame members, furring strips secured to said girth strip, an end wall sheet secured to said girth strip at the end of the car body, and sheathing secured to said furring strips and forming a portion of the side wall. 115 120

6. In a car body, in combination with vertical side frame members, a girth strip passing through and secured to said vertical frame members, an end wall sheet coöperating with the terminal vertical framing members and secured to said girth strip, a furring strip supported on said girth strip, and sheathing secured to the furring strip. 125 130

7. In a car body, in combination with vertical side framing members, a girth strip secured thereto and extending beyond the terminal one thereof, the projecting end of said girth strip being provided with a laterally directed portion, an end sheet applied at the end of the car body and provided with an aperture for the reception of the projecting end of the girth strip, and a member removably secured to said end sheet and adapted to engage the laterally directed portion of the girth strip to secure the end sheet in place.

8. In a car body, a girth strip secured to vertical side framing members and projecting beyond the corner post, an end sheet secured to said girth strip, and side wall sheathing secured to said girth strip.

9. In a car body, an end structure comprising conjoined metallic end wall sections corrugated and connected to form co-operating horizontally disposed tension and compression members, girth strips secured to side framing members, and means for securing the ends of said tension and compression members to said girth strips.

10. In a car body, an end structure comprising conjoined metallic end wall sections corrugated and connected to form a horizontally disposed strengthening beam extending from side to side of the body, girth strips passing through and secured to vertical side framing members, and means for securing the extremities of said beam member to said girth strips.

11. In a car body, an end wall sheet, a girth strip secured to vertical side framing members and provided with a furring strip for the attachment of sheathing and having its extremity adapted for the attachment of the end wall sheet.

12. In a car end, a wall sheet having a marginal flange deflected at an angle from the body portion, said sheet being provided with a corrugation connecting said flange and said body portion and extending across the angle therebetween, means for securing the body portion to a frame member, and means for upholding the flange against tilting movement relative to said framing member.

13. In a car end, a wall portion formed with a longitudinally extending portion offset from the major plane thereof to provide a beam member, and a plate connected at 55 opposite sides of said offset portion and having stiffening corrugations disposed within said offset portion.

14. In a car end, a pair of wall members having portions offset from their major 60 plane to provide a beam member, and a plate attached to said wall members at either side of said offset portions to provide a co-operating beam member, said plate being provided with stiffening corrugations 65 disposed between said offset portions.

15. In a car end, a pair of sections having their meeting edges offset from their major plane and joined together, said sections being provided with transverse corrugations 70 extending at an angle to their connected edges, a tie plate connecting said sections substantially in their major plane, said tie plate being provided with corrugations extending in the direction of said transverse 75 corrugations.

16. In a car end, a pair of sections having their meeting edges offset and connected together, said sections being provided with transverse corrugations extending at an 80 angle to their meeting edges, a tie plate connecting said sections, said tie plate being provided with corrugations in alinement with said transverse corrugations.

17. In a car end, a pair of sections having 85 their meeting edges offset from their major plane and secured together to provide a beam member, one of said sections being provided with a transverse corrugation extending at an angle relative to such beam member, and a tie plate disposed substantially in the major plane of said sections and connected to them, said tie plate being provided with a corrugation in alinement with said transverse corrugation. 90 95

In testimony whereof I hereunto affix my signature, in the presence of two witnesses, this 15th day of May, 1915.

PAUL M. BEARD.
